[57] CLAIM

The ornamental design for a forced air waste oil incinerator, substantially as shown and described.

DESCRIPTION

FIG. 1 is a perspective view of the forced air waste oil incinerator showing my new design;

FIG. 2 is a top view thereof;

FIG. 3 is a front elevational view thereof;

FIG. 4 is an elevational view of the right side of FIG. 1;

FIG. 5 is an elevational view of the left side of FIG. 1; and

FIG. 6 is a rear elevational view of FIG. 1.

The bottom surface of the claimed device is substantially planar and unornamented.
